J. ZAWYRUCHIA

COMBINED COMB AND BRUSH

Filed May 12, 1924

Attorney

UNITED STATES PATENT OFFICE.

JOHN ZAWYRUCHIA, OF EDMONTON, ALBERTA, CANADA.

COMBINED COMB AND BRUSH.

Application filed May 12, 1924. Serial No. 712,874.

This invention relates to improvements in a combined hair brush and comb.

The object of the invention is to provide a simple and compact structure, wherein the 5 comb can be conveniently mounted on the brush back to afford convenient means for using either the brush or comb.

A further object of the invention is to provide means for mounting the comb on the 10 brush back.

The invention also comprehends improvements in the details of construction and arrangement of parts, which will be herein-after described and particularly pointed out 15 in the claims.

In the drawing:

Fig. 1 is a perspective view of the improved combined comb and brush.

Fig. 2 is a similar view showing another 20 way of mounting the comb.

Fig. 3 is a central section taken through the form of the invention shown in Fig. 1.

Fig. 4 is a detail view of a different form 25 of trunnion.

Fig. 5 is a perspective view of another form of the invention.

Fig. 6 is a detail cross section of the same.

The numeral 1 indicates a hair brush comprising a back 2, a handle 3, and bristles 4.

30 In the outer face of the back 2, as shown in Fig. 1, is a groove 5, which extends from the juncture of the handle with the back to a point approximately half way between the ends of the back. On the face of the back 35 beyond the forward end of the groove is a highly polished metal plate 6, which serves as a mirror.

40 The base of a comb 7 is inserted in the groove 5 so that it projects out at right angles to the back of the brush, the side walls of the groove engaging and holding the comb against movement. At opposite ends of the base of the comb are trunnions 8—8 which are of resilient material, and 45 which may be made integral with the comb, as shown in Fig. 3, or made separable, as shown at 8^a in Fig. 4. The resilient trunnions 8—8 fit in sockets 9—9 formed at opposite ends of the groove 5 to hold the comb 50 in fixed relation to the brush when in use.

In lieu of the groove being located in the

brush back, it may be located on one side of the back, as shown in Fig. 2, and if desired, the groove may be formed on the brush back, as shown in Fig. 1, and a slot 10 formed in 55 the side to receive the comb when not in use, as shown in Fig. 5.

When it is desired to use the combined comb and brush, the comb is tilted and one of the resilient trunnions 8 is slipped in one 60 of the sockets 9, and by pressure of the finger on the opposite trunnion to pass the end wall of the slot, the comb is pushed down in place, as shown in dotted lines in Fig. 3. Once the comb is depressed, the resilient 65 trunnion springs into the socket, with the result that the comb becomes locked firmly to the brush. Hence the brush and comb are combined in a simple and efficient article for ready use. Obviously, the comb can be 70 as readily secured on the side of the brush, as on the back, this being a mere matter of design or preference in manufacture.

The resilient trunnions make it possible to withdraw the comb from its groove, by 75 exerting an upward pull, which causes the trunnions to yield and slip out of the sockets, whereupon the comb may be conveniently stored away when the combined brush and comb is not in use.

To provide a convenient place for storing the comb, it may be slipped in the slot 10.

The trunnions may be moulded or otherwise formed as shown in Fig. 4. In this instance, the yielding material when applied 85 to the brush is securely held to the comb proper by lugs 8^b engaging in recesses 8^c in the ends of the comb.

From the foregoing description, it is evident I have provided a simple and convenient structure, which combines in a single article both comb and brush.

What I claim and desire to secure by Letters Patent is:—

1. A brush having a groove formed in its 95 back with undercut end walls, a comb adapted to fit in said groove and having end projections in line with the comb back to engage in the undercut portions of the end walls of the groove.

2. A brush having a groove formed in its back with undercut end walls, a comb adapt-

ed to fit in said groove and having end projections in line with the comb back to engage in the undercut portions of the end walls of the groove, one of said projections being resilient to permit the comb to be inserted in locking position in the groove.

3. A brush having a groove formed in its back with undercut end walls, a comb adapt-

ed to fit in said groove and having end projections to engage in the undercut portions 10 of the end walls of the groove, the brush back being formed with an opening to slidably receive the comb for storage of the latter.

In testimony whereof I affix my signature
JOHN ZAWYRUCHIA. [L.S.]
